5. A combination air duct and girder having a rectangular tube 15 provided at opposite ends with end closures 16 and having formed therein at longitudinally spaced intervals in its side walls air discharge openings 17. Opening through the bottom wall of the girder near one

end is an air intake opening 18 to which the discharge end of air circulating means 19 is coupled. The air circulating means 19 above referred to preferably comprises an air heating furnace having an air circulating fan connected therewith so that air may be circulated through the system mechanically as well as by means of convection.

UNITED STATES PATENT OFFICE

2,569,910

COMBINATION AIR DUCT AND GIRDER

Henry E. Venuti, Newburgh, N. Y.

Application August 8, 1947, Serial No. 767,469

2 Claims. (Cl. 138—69)

1

This invention relates to a combination air duct and girder and has for its primary object to conserve space in a building and at the same time facilitate the distribution of heating or cooling air throughout the building.

Among its features, this invention embodies a combination girder and air duct comprising an elongated rectangular tube having a wall thickness of not less than one-fourth of an inch, said tube having longitudinally spaced air discharge openings in its side walls adjacent the upper edges thereof and said tube having an air inlet opening in its bottom wall near one end.

Other features include a reinforcing truss structure extending longitudinally through the tube to improve its weight-sustaining qualities.

In the drawings,

Figure 1 is a plan view of a building showing this combination air duct and girder in position therein with the lateral air distributing ducts in place, the return duct and the air circulating means coupled thereto,

Figure 2 is a transverse sectional view taken substantially along the line 2—2 of Figure 1,

Figure 3 is a fragmentary sectional view on an enlarged scale taken substantially along the line 3—3 of Figure 1,

Figure 4 is an enlarged fragmentary sectional view taken substantially along the line 4—4 of Figure 1,

Figure 5 is an enlarged fragmentary sectional view taken substantially along the line 5—5 of Figure 1,

Figure 6 is a fragmentary enlarged sectional view taken substantially along the line 6—6 of Figure 1,

Figure 7 is a fragmentary enlarged sectional view taken substantially along the line 7—7 of Figure 1,

Figure 8 is an enlarged sectional view through a truss reinforced girder, and

Figure 9 is a sectional view taken substantially along the line 9—9 of Figure 8.

Referring to the drawings in detail, a building designated generally 10 comprises a basement floor 11 from which rise side walls 12 between the upper and lower ends of which a floor 13 is supported by the side walls 12 and a girder designated generally 14.

The girder 14 above referred to comprises an elongated rectangular tube 15 provided at opposite ends with end closures 16 and having formed therein at longitudinally spaced intervals in its side walls air discharge openings 17. Opening through the bottom wall of the girder near one

2

end is an air intake opening 18 to which the discharge end of air circulating means 19 is coupled. The air circulating means 19 above referred to preferably comprises an air heating furnace having an air circulating fan connected therewith so that air may be circulated through the system mechanically as well as by means of convection.

Leading from the tube 15 are air conveying ducts 20 which discharge through suitable gratings 21 into the various spaces or enclosures within the building 10. Rotatably supported on shafts 22 which extend through the ducts 20 adjacent the ends which open into the tube 15 are dampers 23 by means of which the flow of air through the individual ducts may be regulated. Fixed to one end of each shaft is a lever 24 by means of which the shaft may be rotated in order to adjust the position of the damper 23 within the duct 20.

Extending around the interior of the building immediately beneath the bottom of the tube 15 is an air return duct 26 which is provided at spaced intervals with lateral ducts 27 which lead into the spaces to be heated for withdrawing the air therefrom and circulating it through the air circulator 19. This duct is provided with an air discharge opening which communicates with the circulator 19, so that the air may be extracted from the spaces in the building to be passed through the circulator for heating or cooling, as the case may be, and then discharged from the circulator through the tube 15 and ducts 20 back into the spaces within the building. In this way, the proper temperature within the spaces 35 within the building may be maintained.

In the modified form of the invention as illustrated in Figures 8 and 9, a tube 28 corresponding in all respects to the tube 15 is of rectangular formation and provided with longitudinally spaced air discharge openings 29 to which air distributing ducts 30 are connected. Extending vertically through the tube 28 intermediate opposite sides in longitudinally spaced relation are vertical struts 31 between which diagonal struts 32 extend. These struts cooperate in forming a reinforcing truss which extends longitudinally throughout the length of the tube 28 in order to improve its weight-sustaining qualities.

The side, top and bottom walls of the tubes 15 and 28 are preferably formed of steel plate of not less than one-fourth of an inch in thickness with the junctions welded together to form a transversely rectangular steel tube through the side walls of which the air discharge openings ex-

tend. These openings are preferably located adjacent the upper edges of the side walls of the tube in order to facilitate in the discharge of the air from the tube and at the same time allow sufficient metal between the bottoms of the openings 17 and 29 to sustain the load imposed upon the tube when it is in position in a building to serve as a girder. Obviously, the trussed structure will lend materially to the rigidity of the tube and finds utility particularly when there are long spans between the girder supports.

In use, the tube 15 or the tube 28, as the case may be, is employed as a girder to support the loads imposed upon the floors of buildings and the like and by reason of the tubular structure they also may be employed to serve as ducts through which air may be circulated and distributed to the various spaces within the building in order adequately to heat or cool the same, as the case may be.

While in the foregoing there has been shown and described the preferred embodiment of this invention, it is to be understood that minor changes in the details of construction, combination and arrangement of parts may be resorted to without departing from the spirit and scope of the invention as claimed.

Having described the invention, what is claimed as new is:

1. A load sustaining air duct comprising a longitudinally disposed elongated transversely rectangular tube, longitudinally spaced vertically extending struts within the tube fixed at opposite ends to the top and bottom walls of the tube, diagonal struts within the tube extending between the upper ends of alternate vertical struts to the lower ends of the intermediate, vertical struts, the

side walls of said tube having longitudinally spaced air discharge openings therein adjacent their upper edges.

5 2. A load sustaining air duct comprising a longitudinally disposed substantially rectangular tube, a plurality of longitudinally spaced vertically extending struts within said tube, said struts being terminally secured to the top and bottom walls of the tube, diagonal struts within said tube extending between the upper ends of alternate vertical struts to the lower ends of intermediate vertical struts, a plurality of longitudinally spaced air discharge apertures in the side walls of said tube, said apertures being adjacent and upper edges of said side walls of said tube and medial a pair of adjacent vertical struts.
